THEODOR DE KIMP, OF KIRKSVILLE, MISSOURI.

Letters Patent No. 90,082, dated May 18, 1869.

IMPROVEMENT IN WAGON-SEATS.

The Schedule referred to in these Letters Patent and making part of the same.

To all whom it may concern:

Be it known that I, THEODOR DE KIMP, of Kirksville, in the county of Adair, and State of Missouri, have invented a new and valuable Improvement in Spring-Wagon Seats; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of a longitudinal section of my device.

Figure 2 is a transverse section of the same.

My invention relates to wagon-seats; and

It consists, mainly, in constructing and arranging wooden springs under such seats, with clutches, at their respective ends, to fit over the sides of wagon-boxes, and in means for clamping such springs with great firmness, under the centre of the seat, and thereby holding them securely.

The letter A of the drawings, represents my wagon-seat, and

Letters B are two wooden springs, held in place by means of the blocks *a* and *c*, and the screws *s*, as shown on figs. 1 and 2.

The screws *s* are passed through the bottom of the seat, through the springs B, and block *c*, as represented, and when well adjusted, serve to clamp the springs rigidly between the blocks *a* and *c*, and hold them with great firmness and security.

The letters *v* are clutches, affixed to the ends of springs B, the office of which is to clutch over the sides of the wagon-body, and thereby keep the seat in place.

The above-named devices enable me to furnish a removable wagon-seat, easily adjusted to the body of a lumber-wagon, at once neat, durable, and convenient.

What I claim as my invention, and desire to secure by Letters Patent, is—

The combination and arrangement of the wagon-seat A, wooden springs B, with their clutches *v*, blocks *a* and *c*, and screws *s*, substantially as and for the purposes herein specified.

In testimony that I claim the above, I have hereby subscribed my name in the presence of two witnesses.

THEODOR DE KIMP.
